UNITED STATES PATENT OFFICE

FRANK VIRCHOW, OF WATERLOO, WISCONSIN

KITCHEN CABINET

Application filed June 3, 1931. Serial No. 541,869.

The present invention relates to a cabinet construction and has for its prime object to provide a table incorporated in the cabinet construction in such a manner that it may be folded to form one of the walls of the cabinet 5 or may be extended into a position in extension of the cabinet when desired to be used.

Another very important object of the invention resides in the provision of a cabinet of this nature which is exceedingly simple in 10 its construction, easy to manipulate, thoroughly efficient and reliable in use, and otherwise well adapted to the purpose for which it is designed.

With the above and numerous other objects in view as will appear as the description 15 proceeds, the invention resides in certain novel features of construction, and in the combination and arrangement of parts as will be hereinafter more fully described and 20 claimed.

In the drawings:

Figure 1 is a perspective view of the cabinet embodying the features of my invention.

Figure 2 is a vertical transverse section therethrough taken substantially on the line 25 2-2 of Figure 1.

Figure 3 is a view similar to Figure 2 but showing the table in extended position.

Figure 4 is a horizontal sectional view 30 taken substantially on the line 4-4 of Figure 3.

Figure 5 is a vertical section taken substantially on the line 5-5 of Figure 4.

Figure 6 is a detail section taken substantially on the line 6-6 of Figure 4.

Figure 7 is a sectional view taken substantially on the line 7-7 of Figure 3, and

Figure 8 is an inside view of the table 40 structure.

Referring to the drawings in detail it will be seen that numerals 5 denote end walls, numeral 6 a top and numeral 8 a front wall. The front wall 8 extends from the top 6 and 45 terminates a short distance downwardly therefrom. This front wall 8 has an opening through which is slidable a drawer 9 on in-turned flanges 10 at the bottom ends of plates 11 which depend from the top 6 inwardly at 50 the side walls 5.

A combination front wall section and table 55 comprises a leaf section 16 hinged as at 23 to the fixed front wall section 8. A plate 12 is connected with the section 16 in alinement with said section through the medium of a pair of fixed cleats 19 secured at one end to the under or inner side of the leaf section 16 in any suitable manner and at said ends the cleats 19 are connected by a cross bar 21. A pair of cleats 20 are suitably secured to the inner or under side of the plate 12 and adjacent the free end of the plate 12, the cleats 20 are connected by a cross bar 22. Cleats 19 are provided with grooves and cleats 20 are provided with tongues engaging the grooves of 60 the cleats 19 whereby a slidable connection is provided between plates 12 and 16 so that when the plate 12 and leaf 16 are in horizontal position, plate 12 may be slid outwardly therefrom thus providing as it were an extensible table top and between the leaf section 16 and plate 12 thereof there may be arranged 65 one or more auxiliary leaves (not shown) to be supported in position by the cleats 19, 20 in a manner similar to extension table now 70 in use and well known in the art.

A pair of legs 17 are hinged as at 18 to the plate 12 adjacent the lower or outer edge thereof and adapted to be folded against the inside of the plate 12 and leaf 16 as suggested 75 in Figure 8 when plate 12 and leaf 16 are in vertical alinement with one another and with the front wall section 8, or in other words in the position suggested in Figures 1 and 2.

Manifestly when the combined front wall 85 and table top is to be used as a table the section or leaf 16 together with plate 12 are swung outwardly to the position shown in Figure 3 and the legs 17 also swung to a supporting position.

With the parts in the position shown in Figure 3 a relatively small table extension for the cabinet is provided and this table extension may be increased by the addition of the usual table leaf in the manner hereinbefore suggested.

The plate 12 is also provided with an opening, and a door 15 for closing the opening is provided, and is hinged as at 14. Thus provision is made for access to the interior of the 100

lower portion of the cabinet when the parts 12 and 16 are in vertical or wall forming position.

An auxiliary cabinet 25 may be mounted on the top 6 to rise therefrom. Inside the 5 lower cabinet there may be provided a shelf 26 terminating a distance from the front edges of the walls 5.

It is thought that the construction, operation, utility and advantages of this invention 10 will now be quite apparent to those skilled in this art without a more detailed description thereof.

The present embodiment of the invention has been described in considerable detail 15 merely for the purposes of exemplification since in actual practice it attains the features of advantage enumerated as desirable in the statement of the invention and the above description.

20 It will be apparent that changes in the details of construction, and in the combination and arrangement of parts may be resorted to without departing from the spirit or scope of the invention.

25 Having thus described my invention, what I claim as new is:

A combined cabinet and table comprising in combination, a drawer, an extension table, 30 a front wall section having an opening through which said drawer is slid able and said extension table including a section hinged to the front wall section, cleats secured at one end to said hinged section, a sliding section, cleats secured to the sliding section 35 and having sliding engagement with the first named cleats, hinged legs connected with said sliding section, and a door arranged in said sliding section to afford access to the cabinet beneath said drawer.

40 In testimony whereof I affix my signature.
FRANK VIRCHOW.
